ROLL-HANDLING AND CONTROL MECHANISM FOR CLOTH INSPECTING MACHINES

Elmer F. Clark and Leland F. Remington,
Worcester, Mass., assignors to Curtis & Marble
Machine Company, Worcester, Mass., a corpora-
tion of Massachusetts

Application January 24, 1949, Serial No. 72,432

5 Claims. (Cl. 242—55)

1

This invention relates to machines in which lengths of cloth are inspected for imperfections or other defects. It is common to wind the inspected cloth into a cloth roll, and to continue this operation until the cloth roll is of relatively large diameter and of substantial weight.

It is one object of our invention to provide improved roll-handling mechanism by which the removal of a large and heavy roll of cloth is much facilitated.

A further object is to provide improved control devices by which the direction of travel of the cloth may be reversed when desired, and by which the cloth roll may be conveniently released for replacement while the roll is still horizontally supported.

Our invention further relates to arrangements and combinations of parts which will be herein-after described and more particularly pointed out in the appended claims.

A preferred form of the invention is shown in the drawings, in which

Fig. 1 is a side elevation of a cloth inspecting machine embodying our improvements;

Fig. 2 is a perspective view of the cloth winding arbor and its supporting, driving and reversing mechanism;

Fig. 3 is a plan view, partly in section, of the mechanism shown in Fig. 2;

Fig. 4 is a front elevation of a control bracket, with a hand lever shown in section, and looking in the direction of the arrow 4 in Fig. 3;

Fig. 5 is an end elevation, partly in section, and looking in the direction of the arrow 5 in Fig. 2;

Fig. 6 is a wiring diagram for the motor control; and

Fig. 7 is a detail sectional view to be described.

Referring to the drawings, the cloth inspecting machine in which our improvements are embodied comprises a frame 10 having an inspecting table 11 mounted in the upper part of the frame and adapted to be secured in a selected inclined position by a clamping screw 12 extending through an arcuate slot 13 in a bracket 14 secured to the back side of the table 11.

The cloth C to be inspected is delivered to the machine in the form of a large supply roll R, which is rotatably mounted in fixed brackets 16 at the back of the machine and which is held from displacement by friction-lined clamps 17 drawn downward by springs 18. These clamps also act as brakes to prevent free forward rotation of the roll by inertia when the machine is stopped.

2

The cloth C as it leaves the roll R passes upward to a driven feed roll or drum 20 rotatably mounted in fixed brackets 21. The cloth C then passes under a pressure roll 22 supported in swinging arms 23 secured to the frame 10. The cloth next travels around a guideroll or guiding member 25 at the upper back edge of the table 11, and is then drawn downward over the table 11 and around a lower guideroll or guiding member 26 at the lower front edge of the table.

10 The cloth then passes behind a winding arbor 30 and then downward around a drum 32 and again upward to the arbor 30, on which it is now wound. A freely-rotating roll 34 is pressed 15 against the cloth C by a spring 35 as the cloth passes under the drum 32. The drum 32 has a bevel gear connection to a clock or measuring device K by which the yardage on the roll of inspected cloth is indicated.

20 The driving mechanism for the inspecting machine comprises a motor M having a two-part variable-speed pulley 39 connected by a V-belt 40 to a relatively larger pulley 41 on a shaft 42. The two parts of the variable-speed pulley 39 are 25 yieldingly pressed together. A sprocket 43 is loose on the shaft 42 and is connected by a chain 44 to a sprocket 45 on a shaft 46 rotatable in fixed bearings in the frame 10.

20 The sprocket 43 may be connected to the shaft 30 42 by a clutch 48 controlled by a yoke lever 49 which is operatively connected with a treadle lever 50. When the treadle lever 50 is pushed downward, the yoke lever 49 will be moved to engage the clutch 48, so that the sprocket 43 will 35 rotate with the shaft 42 and pulley 41. A spring 54 holds the treadle lever 50 normally in raised position, with the clutch 48 open.

30 The motor M is mounted on a base 56 which may be moved forward or rearward by a hand screw 57 to vary the speed by adjusting the radial driving position of the belt 40 with respect to the two-part pulley 39. The shaft 46 drives the feed roll 20 at uniform speed through a belt 57a.

35 The shaft 46 also carries a sprocket 60 connected by a chain 61 to a sprocket 62 which rotates the winding arbor 30. The sprocket 62 is connected to a short shaft 65 (Figs. 2 and 3) through a slip-friction device 66 which may be of any usual construction.

40 The shaft 65 is connected to turn a winding shaft 70 which is rotatable in bearings 71 in a post 72 (Fig. 2) having a downwardly extending stud 73 swinging in a fixed bracket 74.

45 The winding arbor 30 may be of the sectional 55 type which expands when under winding ten-

sion, and which contracts when the tension is relieved. This facilitates removal of the cloth from the winding arbor. The expanding arbor in itself forms no part of the present invention.

The driving connection between the shaft 65 and the winding shaft 70 comprises a short stud 80 (Fig. 7) which may be projected into an axial recess 81 in the free end of the shaft 70. The stud 80 is mounted in a sleeve 82 keyed to the shaft 65 but axially slidably thereon. Clutch teeth 84 are provided on the outer end of the sleeve 82, and corresponding teeth 85 are provided on the enlarged adjacent end of the shaft 70.

The sleeve 82 has an annular groove 86 to receive pins 87 in a forked control lever 88 (Figs. 2, and 7) which is loosely pivoted on a stud 89 and which is provided with a handle 90. By swinging the lever 88 to the right in Figs. 3 and 7, the two sets of clutch teeth 84 and 85 may be disengaged, and by further swinging movement to the right, the stud 80 may be entirely withdrawn from the recess 81 in the shaft 70.

The pivot stud 89 depends from a control and reversing switch S on an arm 92 (Fig. 2) which extends rearward from a fixed bearing 93 for the shaft 65. A spring 95 (Fig. 5) is mounted on the pivot stud 89 and tends to normally raise the rear end of the lever 88. This rear end of the lever underlies a plunger 100 in the reversing switch S which controls the motor M. The plunger 100 positions a contact plate 101 (Fig. 6) in the switch S.

The handle 90 of the lever 88 extends forward through a slot in a fixed bracket 103 (Figs. 3 and 4) which may be mounted on the fixed bearing 93. The slot in the bracket 103 has a semi-depressed notch 105, a fully depressed notch 106, and a raised and lateral extension 107.

When the handle 90 is in the notch 105, the switch S completes a circuit to drive the motor M in the forward direction. This circuit is from the line wire L (Fig. 6) through the wire 110 to the plate 101, and then through the contact stud 111, wire 112 and the forward winding 133 of the motor M to the line wire L'.

Placing of the handle 90 in the notch 105 also shifts the sleeve 82 (Fig. 7) to its extreme left-hand position, with the stud 80 extending into the recess 81 and with the sets of clutch teeth 84 and 85 in driving engagement.

The winding shaft 70 and winding arbor 30 are thus rotated to wind up the cloth C as it is drawn downward over the inspecting table 11.

When the handle 90 is moved to the fully depressed slot 106, the handle 90 is depressed by the spring 95 and the rear end of the lever 88 is raised, thus moving the plunger 100 upward and shifting the connections to the motor M. The circuit is then from the plate 101 through the contact stud 115, wire 116 and the reverse winding 117 of the motor M to the line wire L'.

At the same time, the clutch teeth 84 and 85 are separated but the stud 80 is only partially withdrawn from the recess 81, thus permitting the shaft 70 and winding arbor 30 to be rotated freely backward but preventing swinging displacement thereof.

If the handle 90 is shifted to the extreme right-hand end of the raised lateral slot extension 107 (Fig. 4), the rear end of the lever 88 will be moved downward, which permits corresponding downward movement of the plunger 100 and thus causes the motor M to resume forward rotation. At the same time, the stud 80 is fully withdrawn

from the recess 81, so that the shaft 70 and the winding arbor 30 may be swung forward as indicated in broken lines in Fig. 2. The shaft and arbor will still be firmly supported horizontally by the stud 73 (Fig. 2) and bracket 74, and no downward swing of the arbor can take place.

The driving connections are so proportioned that the peripheral speed of the winding arbor 30 is slightly greater than the peripheral speed of the driven feed roll or drum 20. As soon as winding begins, the excess surface speed of the winding arbor and roll of cloth thereon is taken care of by slippage in the friction device 66, which slippage increases as the size of the roll of cloth on the winding arbor 30 increases.

The machine is designed for very convenient operation which is briefly as follows: The handle 90 is first placed in the semi-depressed slot 105 so that the motor M will be in forward rotation, with the stud 80 in the recess 81 and with the clutch teeth 84 and 85 engaged.

The motor rotates the shaft 42 (Fig. 1) idly until the treadle lever 50 is depressed. The feed drum 20 is then rotated to draw cloth upward from the supply roll R, and the winding arbor 30 is rotated to wind the cloth into a new roll after inspection and as it is drawn downward from the table 11. During this inspecting and cloth winding operation, the travel of the cloth may be stopped at any time by removing the foot pressure on the treadle lever 50.

If it is desired to reverse the travel of the cloth for further inspection or for any other purpose, the handle 90 is shifted to the fully depressed slot 106, which action reverses the direction of rotation of the motor M, and disengages the clutch teeth 84 and 85. The cloth can then be drawn backward by the roll 20, as the winding arbor 30 is now free to be rotated backward.

When the roll of cloth on the winding arbor 30 has reached limiting diameter, the handle 90 is shifted to the extreme right-hand end of the raised slot extension 107, thus fully withdrawing the stud 80. The winding arbor 30, with the roll of inspected cloth thereon, may then be swung forward on the stud 13, and the roll of cloth will remain horizontally supported until the cloth is manually removed axially from the winding arbor.

The winding arbor is then returned to the full line position of Fig. 2, after which the handle 90 may be returned to the slot 105 for a further winding operation.

The direction of rotation of the motor M is thus controlled by the single handle 90, which also engages and disengages the teeth 84 and 85 which drive the arbor 30, and which advances and withdraws the stud 80 which supports the free end of the shaft 70 and of the winding arbor 30.

Our improved cloth inspecting machine is thus particularly adapted for convenient operation and has been found very satisfactory in actual use.

Having thus described our invention and the advantages thereof, we do not wish to be limited to the details herein disclosed, otherwise than as set forth in the claims, but what we claim is:

1. In a cloth inspecting machine, a winding arbor, means to support one end of said arbor for swinging movement in a substantially horizontal plane only, a motor to drive said machine and arbor, and a single manual means effective by a continuous movement to axially disengage said motor from said arbor and to simultaneously

reverse said motor and machine, and said arbor being thereafter free to rotate backward in its initial axial position so long as said motor is running in reverse.

2. In a cloth inspecting machine, a winding arbor, spaced bearing means to support one end of said arbor for swinging movement in a substantially horizontal plane only, a motor to drive said machine and arbor, and manual means effective to axially separate said supporting and driving mechanism from said winding arbor, thereby leaving said arbor free to swing forward for cloth removal.

3. In a cloth inspecting machine, a winding arbor, a member having axially spaced bearings for one end portion of said arbor, an upright post for said bearing member which is mounted for free angular movement about a substantially vertical axis, combined driving and supporting means for the other end of said arbor, and manual means to withdraw said combined driving and supporting means axially from engagement with said arbor, thereby leaving said arbor free to swing about the axis of said post while the arbor is firmly supported by said spaced bearings.

4. In a cloth inspecting machine, a winding arbor, a horizontal bearing for one end of said arbor, means to support said bearing for swinging movement about a vertical axis only, disengageable supporting means for the other end of said arbor, means to drive said machine and said winding arbor, and a single manual means effective to release the winding arbor for continuous free rotation in supported position and about its original axis of rotation and to simultaneously 35 reverse the driving means.

5. In a cloth inspecting machine, a winding arbor, a member having axially spaced bearings for one end portion of said arbor, an upright post for said bearing member which is mounted for free angular movement about a substantially vertical axis, driving means and supporting means for the other end of said arbor, and manual means effective by a partial axial withdrawing movement to disengage said driving means from said winding arbor and by a further axial withdrawing movement to disengage said supporting means from the associated end of said winding arbor, thereby leaving said arbor free to swing about the axis of said post while the arbor is firmly supported by said spaced bearings.
